CLAIM

The ornamental design for a spinner for wheels, as shown and described.

DESCRIPTION

FIG. 1 is a front perspective view of a first embodiment of the spinner for wheels showing my new design, with a flat top and two wings;

FIG. 2 is a top plan view thereof;

FIG. 3 is a front elevational view thereof;

FIG. 4 is a right side elevational view thereof;

FIG. 5 is a front perspective view of a second embodiment of the spinner for wheels showing my new design, with a dome top and two wings;

FIG. 6 is a top plan view thereof;

FIG. 7 is a front elevational view thereof;

FIG. 8 is a right side elevational view thereof;

FIG. 9 is a front perspective view of a third embodiment of the spinner for wheels showing my new design, with a flat top and three wings;

FIG. 10 is a top plan view thereof;

FIG. 11 is a front elevational view thereof;

FIG. 12 is a right side elevational view thereof;

FIG. 13 is a front perspective view of a fourth embodiment of the spinner for wheels showing my new design, with a dome top and three wings;

FIG. 14 is a top plan view thereof;

FIG. 15 is a front elevational view thereof; and,

FIG. 16 is a right side elevational view thereof.
